UNITED STATES PATENT OFFICE.

TALBOT G. MARTIN, OF CHICAGO, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

1,312,702.

Specification of Letters Patent.

Patented Aug. 12, 1919.

Application filed August 8, 1912, Serial No. 713,957. Renewed August 31, 1918. Serial No. 252,258.

To all whom it may concern:

Be it known that I, TALBOT G. MARTIN, a citizen of the United States, and resident of Chicago, in the county of Cook and State of

5 Illinois, have invented certain new and useful Improvements in Measured-Service Telephone Systems, of which the following is a specification.

My invention relates to semi-automatic 10 telephone systems, and more particularly to improved means for registering calls in such systems.

Among the objects of my invention are to provide in a semi-automatic telephone 15 system a meter for the calling subscriber's line which is automatically operated to register the call upon the response of the called subscriber.

A more specific object of my invention is 20 to provide for this automatic operation of the meter in a semi-automatic system in which the calling subscriber obtains connection with the manual switchboard through a plurality of trunking switches.

25 A further novel feature of my invention is the manner in which the meter is operated by a strengthened impulse, which impulse is strengthened to operate the meter automatically upon the response of the called 30 subscriber.

These and other objects of my invention will be more readily understood by reference 35 to the accompanying drawings, in which I have illustrated a semi-automatic system in which the features of my invention are embodied.

In the accompanying drawings—

Figures 1 and 2 taken together show a 40 complete connection between a calling substation A' and a called substation A² in a system embodying the principles of my invention.

Figs. 3 and 4 represent a connection between a calling substation A³ and a called 45 substation A⁴ in a system similar to that represented in Figs. 1 and 2, but employing slightly different circuit arrangements.

The telephone system represented herein is of that type in which the connections between the calling and called subscribers are 50 completed manually by an operator, but in which the subscribers' lines do not have individual answering terminals at the central office, the answering terminals being common to all the lines, and each line being

provided with apparatus for automatically connecting it with an idle answering terminal upon the initiation of a call. For instance: Referring to Fig. 1, the line of the substation A' is equipped with one or more 60 multiple jacks J at the central office in the usual manner, but instead of the usual answering jack, said line is provided with an automatic trunk-selecting switch C'. This automatic switch C', together with a number 65 of other similar switches, has access to a common group of trunk lines, each of which leads to a so-called secondary trunk-selecting switch C⁵. Like the subscribers' individual switches, the secondary switches are 70 also divided into groups, each group of switches having access to a common group of trunk lines each of which leads to an operator's cord circuit O which terminates in a plug P (Fig. 2). The trunk lines leading 75 from each group of subscribers' primary switches C' are uniformly distributed among the various groups of secondary switches C⁵, and the trunk lines leading from each group of secondary switches C⁵ 80 are distributed among the various operators' positions on the manual board. With this arrangement the answering terminals on the manual switchboard may all be made common to all the substations in the exchange, 85 and the calls from the various substations and the calls from the various substations will be distributed among the different operators. Any subscriber wishing to make a 90 call simply removes his receiver from the switch hook, whereupon the switches C' and C⁵ automatically operate to extend his line to an idle plug P and to signal the operator. The operator completes the connection by inserting the plug P into the multiple jack of the line called for in the usual manner. 95

The substations shown herein may be of any suitable common battery type. Referring to the substation A', the substations shown herein comprise the usual receiver 2, transmitter 3, switch hook 4, ringer 5 and 100 condenser 6.

The primary and secondary trunk-selecting switches C' and C⁵ are of the general type of switches disclosed in the *Western Electrician* of Chicago, Illinois, of January 105 25, 1908, being of the particular type, however, shown in British patent to A. E. Keith, No. 1421 of 1910. These line switches, as is well known, are each provided with a plunger which, when idle, is 110

always maintained opposite the bank terminal of an idle trunk line by a so-called master switch, and upon the operation of said switch its plunger is forced into the 5 bank of said idle trunk line to connect the line leading to it with said trunk. The master switches shown herein are somewhat different from those shown in said British Patent No. 1421 of 1910. Referring to the 10 master switch D' (Fig. 1), 18 is the usual plunger shaft through the medium of which the master switch controls the plungers of the trunk-selecting switches. The plunger shaft 18 is connected with a rotary shaft 19 in 15 such a manner that, as the shaft 19 is rotated back and forth, the plunger shaft 18 is caused to oscillate about said shaft 19 as an axis. The shaft 19 is adapted to be rotated in one direction by a spring 20 and in the other 20 direction against the tension of said spring by a solenoid 21. Secured to the shaft 19 there is a cam member 22 provided along its outer edge with a series of notches 23, one for each trunk line to which the line switches 25 have access. The shaft 19 is normally locked against rotation in either direction by the engagement of the lever 24 with one of the notches 23. The lever 24 is controlled by the armature of the relay 25 in such a 30 manner that, when said relay is energized, the lever is withdrawn from the cam so as to unlock the shaft 19. The speed of rotation of the shaft 19, and therefore the speed of the plunger shaft 18, is controlled 35 through the medium of a suitable governor 26. Associated with the master switch there is a relay 27 the springs of which, upon being operated, are locked in their operated positions by the engagement of the spring 40 28 with a detent on the under side of the spring 29. The springs of the relay 27 are unlocked by the arm 30 when the shaft 19 reaches the limit of its travel in one direction. When the shaft 18 reaches the limit 45 of its travel in the other direction, the arm 31 forces the spring 32 into engagement with the spring 33. The master switch is also provided with a bank of contacts, comprising a common segment 34 and an individual 50 contact *a* for each of the trunk lines to which the switches C' controlled by the master switch have access. A wiper 35 keeps the common segment 34 in electrical contact with the individual contact *a* corresponding 55 to the trunk line before which the plungers of the idle line switches are resting. In general, the operation of the master switch is as follows: Whenever a line switch whose plunger is in engagement with the plunger 60 shaft 18 is operated to seize a trunk line, the relay 25 is energized to unlock the shaft 19. The spring 20 thereupon begins to rotate said shaft to cause the plunger shaft to move the idle plungers away from the trunk 65 line just seized and onto an idle trunk line.

When the idle trunk line is reached, the relay 25 deenergizes and again locks the plunger shaft. When the plungers in their operation pass beyond the last trunk line, the arm 31 forces the spring 32 into contact 70 with the spring 33, whereupon the relay 27 is energized and closes the circuit of the solenoid 21. The solenoid, upon energizing, rotates the shaft 19 back to its initial position so as to bring all the plungers which 75 are in engagement with the plunger shaft back to a position opposite the first trunk line and to restore the tension to the spring 20. When the plunger shaft reaches its initial position, the arm 30 unlocks the springs 80 of the relay 27, which permits the solenoid to deenergize and the plunger shaft to come to rest. The master switches D², D³ and D⁴ are all similar to the master switch D'.

Between the master switches D' and D² 85 (Fig. 1) there is shown a device L the purpose of which will be described hereinafter. This device comprises a set of contacts *b*, a common segment 37 and a wiper 38. The wiper 38 is adapted to be rotated 90 over the contacts *b* step by step by a motor magnet 39. The magnet 40 is a retaining magnet and, while energized, is adapted to maintain the wiper 38 in any advanced position. The springs 41 are separated by the 95 wiper 38 when it engages the last contact *b*.

The operator's cord circuit O is provided with the usual answering and calling supervisory signals 42 and 43 and the necessary relays for controlling the same. The double-wound relay 44 is bridged across the answering end of the cord through the springs of a reversing relay 45. The ringing key 46, when depressed, becomes locked in its operated position, but may be unlocked by the energization of the magnet 47. The interrupter devices 48 and 49 are adapted to alternately connect the battery B' and the ringing current generator 50 with the 105 relay 47.

The substation A' is shown provided at the central office with a call register or meter 51 which is controlled by a double-wound magnet 52. The windings of the magnet 52 are so proportioned that it requires the energization of both windings in 110 the same direction to attract the armature, said armature being unaffected by the energization of either winding alone, or by the energization of the two windings in opposition to each other.

Referring to Fig. 3, it will be seen that the line switch C³ is slightly different from the line switch C' (Fig. 1) in that it has no armatures corresponding to the line armature 219 115 and the cut-off armature 218 shown in Fig. 1, these armatures in the switch C³ being controlled by separate relays 53 and 54. The relays 53 and 54 correspond to the usual manual system. The line of the substation 120

- A³ is provided with a central office meter 55 which is controlled by a single-wound magnet 56. The operator's cord circuit O', as shown, differs somewhat from the cord O shown in Fig. 1, which difference will be readily understood from the description which is to follow. Allotted to the cord circuit O' there are two call registers or meters 57 and 58. The meter 58 is adapted to register 10 all calls which are made through the medium of the cord O', while the meter 57 registers the successful calls—that is, the calls which are actually answered by the called subscriber.
- 15 Throughout the drawings there is shown a plurality of batteries B', B² and B³ for furnishing current for operating the central office relays and switches. It will, of course, be understood that in practice these might 20 be one and the same battery, but for convenience of illustration they are shown as separate batteries.
- Having given a general description of the apparatus, it will now be explained in detail 25 how the calling subscriber at the substation A' may obtain connection with the subscriber at the called substation A². As is well known, the plunger of the line switch C', when idle, is always maintained opposite the terminal of an idle trunk line. When 30 the calling subscriber removes his receiver preparatory to making a call, the closure of the hook switch 4 with its contact completes a bridge across the calling line through the transmitter and receiver of the calling substation, whereupon the line winding 59 of 35 the switch C' becomes energized. The winding 59, upon energizing, attracts the armature 219, whereby the circuit of the operating winding 60 is closed. The winding 60, 40 upon energizing, attracts the plunger arm 7 and the cut-off armature 218. The armature 218 operates to disconnect the line winding 59 from the line, while the plunger arm 7 causes the plunger to be thrust into the 45 group of contact springs forming the terminal of the trunk line before which it is being held and forces the springs 9 and 11, 13 and 15 into contact with the springs 10, 12, 14 and 16, respectively, as shown. The 50 engagement of the springs 9 and 11 with the springs 10 and 12, respectively, extends the line connection over the trunk conductors 62 and 63 to the switch C⁵. The engagement of the springs 15 and 16 of the 55 switch C' completes a circuit extending from ground G' through said springs 15 and 16, winding 64 of the switch C⁵ and the springs 65, 66, relay 67, back contact of the armature 60 68, springs 69 of the relay 70 in the master switch D² and through the contact 71 to the battery lead 72, thence through battery B' to ground G'. The winding 64, upon energizing, attracts its plunger arm 72^a, which 65 operates in the same manner as the plunger arm of the switch C' to extend the line connection over the trunk conductors 73 and 74 to the cord O. When the plunger arm 72^a is attracted it also forces the spring 75 into engagement with the spring 65 and the 70 spring 65 out of engagement with the spring 66, whereby the operating winding 64 is connected to battery directly through the high resistance holding winding 76 to reduce the current consumption while the switch is being held in its operated position. When the connection is extended to the cord O by the secondary switch C⁵, the relay 44 in the cord becomes energized over a circuit extending from ground G² through the upper winding 80 of said relay, back contact of the spring 77, trunk conductors 74 and 62, thence through the substation A' and back over the other side of the line through the left-hand winding of the meter magnet 52, trunk conductors 63 and 73, back contact of the spring 76^a and the lower winding of the relay 44 to the battery lead 72. The relay 44, upon energizing, closes the circuit of the lamp 42, which circuit extends from ground G³ 90 through the back contact of the spring 78 and the front contact of the spring 79 and through said lamp to the battery lead. The closure of the contact 80, upon the energization of the relay 44, completes a circuit extending from ground G⁴ through said contact 80, relay 81, springs 82 and 83, 14 and 13 and the holding winding 84 of the switch C' to the battery lead 72 for the purpose of maintaining the switch C' in its operated 100 position after the line winding 59 has deenergized and opened the circuit of the operating winding 60. During the interval which might elapse between the time when the line winding is deenergized and the time 105 when the relay 44 of the cord has operated to close the circuit of the winding 84 of the switch C', as above described, said winding is energized over a circuit extending from ground G' through its own bank contacts 110 15 and 16, contact 85 of the relay 67, springs 13 and 14 and the winding 84 to the battery lead. The relay 67 is energized in series with the operating winding of the line switch C⁵ and, being a slow acting relay, remains 115 in its energized position for a short time after the switch C⁵ has operated. The relay 81, which is included in the circuit of the holding winding 84 of the switch C', is energized in series with said winding, but 120 has no particular function at this time. The purpose of this relay will be fully described hereinafter.
- When the springs 15 and 16 of the switch C' are forced into contact upon the operation of said switch, a circuit is closed extending from ground G' through the springs 15 and 16, contact point 86 (which is assumed to correspond to the trunk line leading to the switch C⁵), wiper 35 (which is 130

assumed to be standing on the contact 86 at the time), common segment 34 and the relay 87 to the battery lead 72. The relay 87, upon energizing, closes the circuit of the 5 relay 25, which operates to unlock the plunger shaft and permit the plungers to be moved to an idle trunk line, as hereinbefore described. When the plungers reach a position opposite an idle trunk line, the 10 wiper 35 engages a non-grounded contact and the relay 87 deenergizes, permitting the relay 25 to in turn deenergize to bring the master switch to rest. During the time the master switch is operating, the operative 15 windings of all the line switches C which it controls are disconnected from the battery lead by the separation of the springs 88 of the relay 25, so that no line switch can be operated while its plungers are in motion. 20

When the bank springs 89 and 90 are forced into contact upon the operation of the secondary switch C⁵, the master switch D² operates in the same manner as explained 25 for the master switch D' to advance the plungers of the idle secondary switches to an idle trunk line.

Upon observing the signal of the lamp 42, the operator at the cord O operates the 30 listening key K to connect her talking set with the line and inquires the number of the desired station in the usual manner. Upon learning the number of the station desired, the operator inserts the plug P (Fig. 35 2) into the multiple jack of the called line and depresses the ringing key 46. Upon the insertion of the plug into the jack a circuit is closed extending from grounds G⁶ and G⁷ through the relays 91 and 92 in 40 multiple, thence through the third conductor and through the cut-off winding 93 of the called subscriber's switch C² to the battery lead 72. The winding 93, upon energizing, attracts the cut-off armature 94 to disconnect the switch from the line, but is not 45 strong enough to attract the plunger arm 95 from its normal position. The relay 91, upon energizing, closes the contact 96 in the talking circuit and shifts the connection of 50 the ground G⁸ from the front contact spring 200 of the relay 44 to the back contact spring 201 of said relay, whereby the circuit of the lamp 42 is broken. The relay 92, upon energizing, closes the circuit of the answering 55 supervisory lamp 43 at the contact 97. The depression of the ringing key 46 opens the talking circuit between the calling and the called substations, grounds one side of the line at G⁸ and connects the other side 60 of the called line through the relay 47 and the interrupters 48 and 49 to the grounded battery B' and the ringing current generator 50. Through the medium of the interrupters the generator and battery are alternately connected with the line, whereby the called 65

subscriber is rung periodically. When the called subscriber removes his receiver, or as soon thereafter as the interrupter 48 connects battery B' with the line, the magnet 47 is energized and unlocks the key 46, 70 whereby said key is restored to its normal position to disconnect the ringing current from the called line and to restore the talking connection. The called substation is provided with talking current over a circuit which extends from ground G⁹ through the relay 98, springs 99 of the ringing key, ring conductors of the plug P and the jack J², thence through the substation A² and back over the other side of the line, tip conductors of the jack J² and the plug P, springs 100 of the ringing key 46, springs 96 and the relay 101 to the battery lead 72. The relay 98, upon energizing, breaks the 75 circuit of the lamp 43 to signify to the operator that the called subscriber has answered. 80

The function of the relay 101 is as follows: It will be remembered that when the connection was first extended to the cord O by the switches C' and C⁵ the calling substation was provided with talking current through the two windings of the relay 44 in the cord, which current also flows through the left-hand winding of the meter magnet 52 at the switch C'. This current has no 90 effect upon the magnet; however, as it is at this time opposed by current flowing in the right-hand winding of said magnet, the path of this latter current being from ground G⁴ at the cord O over the circuit traced for 100 the winding 84 of the switch C' to the spring 13, thence through the right-hand winding of the magnet 52 and the contact 102 (which is closed upon the operation of the plunger arm 7) to the battery lead 72. When the relay 101 in the cord is energized upon the response of the called subscriber, as explained above, it closes the circuit of the relay 45. The relay 45, upon energizing, transposes the connections between the winding of the 110 relay 44 and the trunk conductors 73 and 74, as a result of which the direction of the current flowing in the calling line, and consequently in the left-hand winding of the meter magnet 52, is reversed. This reversal 115 of the current in the left-hand winding of the meter magnet causes the two windings to now assist each other, and as a consequence the armature of said magnet is attracted and operates to register the call upon the meter 120 51. The magnet 52, upon energizing, also closes the contact 103, whereby the left-hand winding of said magnet is short-circuited. The magnet then remains held in its operated position by the right-hand winding 125 alone, which, although it is not strong enough to operate the armature, is strong enough to hold it in its operated position. The short-circuiting of the left-hand winding renders the meter magnet inoperative to 130

any other changes in the line current, so that the meter is incapable of being operated more than once, even though the called subscriber should move his receiver hook up 5 and down a number of times and thereby reverse the current in the calling line several times.

Upon the completion of the conversation the operator is given the usual disconnect 10 signals by the hanging up of the receivers at the calling and called substations in the following manner: Upon the hanging up of the receiver at the called substation A², the relays 98 and 101 of the cord are deprived of 15 current. The relay 98, upon deenergizing, closes the circuit of the calling supervisory lamp 43. Upon hanging up his receiver the calling subscriber destroys the energizing circuit of the relay 44 in the cord. The relay 44, upon deenergizing, closes the circuit of the lamp 42, said circuit extending from ground G³ through the front contact of the spring 78 and the back contact of the spring 79 and the lamp 42 to the battery lead 72. 20 Upon noting the simultaneous glowing of the lamps 42 and 43 the operator removes the plug P from the jack J². Upon the removal of the plug the circuit of the relays 91 and 92 in the cord is broken. The relay 25 91, upon deenergizing, breaks the circuit of the lamp 42, and the relay 92, upon deenergizing, breaks the circuit of the lamp 43 and also the circuit of the holding winding 84 of the switch C'. The winding 84, upon 30 deenergizing, permits the plunger of said switch to restore to its normal position, whereupon the holding circuit of the switch C⁵ is broken at the springs 15 and 16, and this switch also restores to its normal position, thereby leaving all the apparatus which 35 was employed in the call in a normal position in readiness for another call. Of course, the circuit of the right-hand winding of the meter magnet 52 is broken at the same 40 time the circuit of the winding 84 of the switch C' is broken, and said magnet accordingly deenergizes.

Having given a description of the manner in which a connection is established and released, the purpose and mode of operation 45 of the device L shown between the master switches D' and D² will now be explained. As is well known, the type of switches to which the switches C' and C⁵ belong are so 50 arranged that after a switch has been operated and released, its plunger does not immediately return into locking engagement with the plunger shaft, but remains in front of the bank terminal from which it was last 55 disengaged until the master switch, by subsequent operations, brings the plunger shaft back to the position in which it was standing when said switch was operated. In the 60 system described herein, there are usually 65 more secondary switches C⁵ in a group than

there are trunk lines leading out of said group. It will thus be seen that all of the trunk lines leading out of a secondary group may become busy while there still are idle trunk lines leading from the primary 70 switches into the busy secondary group, and it may be that in some primary group there may be a plunger disconnected from its plunger shaft and standing in front of one of these idle trunk lines leading into the 75 busy secondary group. It is the function of the device L to cause the primary master switches D' to operate to pick up all their idle plungers and bring them into locking engagement with their plunger shaft whenever all of the trunk lines leading out of the secondary group become busy. This is accomplished as follows: It will be remembered that the relay 81 was energized when connection was extended to the cord O. 80 There is one such relay for every trunk line leading to the manual board. There are shown herein the relays 81, 81^a and 81^b belonging to the first, second and last trunk lines of the group which is accessible by the 85 group of switches to which the switch C⁵ belongs. The contacts of these relays are all connected in series, so that when all the trunk lines of the group become busy, and consequently when all the relays 81, 81^a and 81^b 90 become energized, a circuit is closed from ground G²⁸ through the relay 105. The relay 105, upon energizing, closes the circuit of the relay 106 and, by opening the contact 71, disconnects the battery from the master 100 switch D² to prevent it from operating. The relay 106, upon energizing, disconnects the battery from the operating winding 64 of all the idle secondary switches C⁵ of the group and extends a guarding potential from 105 ground G⁸ through the last winding 64 to the corresponding contacts a in the master switch banks of the primary master switches D'. The relay 105, upon energizing, also closes a circuit for the holding magnet 39 of 110 the device L by closing the contact 107, grounds the common segment 37 and closes a circuit through the operating winding 40, said circuit extending from ground G⁹ through the contact 107, contact 108, relay 115 109, contact 41 and the magnet 40 to the battery lead 72. The magnet 40 thereupon energizes and rotates the wiper 38 one step, while at the same time the relay 109 energizes to close the circuit of the relay 110. 120 The relay 110, upon energizing, breaks the circuit of the magnet 40 and the relay 109. The relay 109, upon deenergizing, breaks the circuit of the relay 110, which in turn, upon deenergizing, again closes the circuit of the 125 magnet 40 to cause the wiper 38 to be advanced a second step. It will, therefore, be seen that upon the closure of the contact 107 by the relay 105 the magnet 40 begins to operate to automatically advance the wiper 130

38 step by step, said wiper remaining on each contact during the time which it takes for the relays 109 and 110 to deenergize, and since these relays are both slow acting this time is of some little length. The contacts *b*, which are engaged by the wiper 38, are connected with the starting relays 87 of the respective primary master switches *D'*, so that as the wiper 38 passes over its contacts 5 it closes the circuits of the starting relays of the different primary master switches *D'* in succession, and maintains said circuits closed long enough to permit each master switch to cause its plunger shaft to make at least one 10 complete oscillatory movement, whereby all the plungers are picked up and brought into locking engagement with their plunger shaft. If desired the wiper 38 may be caused to engage a plurality of contacts at each step, so 15 as to cause a plurality of the primary master switches to be operated at one time. After the wiper 38 has passed beyond the last contact, it opens the circuit of the rotary magnet 40 at the springs 41 and, therefore, 20 comes to rest. When one of the trunk lines leading out of the secondary group becomes idle, the relay 105 deenergizes and breaks the circuit of the holding magnet 39, whereupon the wiper 38 returns to its normal position. 25

30 The operation of the apparatus shown in Figs. 3 and 4, through the medium of which connection is extended from the substation *A*³ to the called substation *A*⁴, is, in general, as follows: The operations of the switches *C*³ and *C*⁴ and the master switches *D*³ and *D*⁴ being essentially the same as described in connection with Fig. 1, it is not thought necessary to explain the same in detail. Upon the removal of the receiver at the 35 calling substation *A*³, the line relay 53 is energized and closes the circuit of the operating winding 111 of the switch *C*³, whereupon the connection is extended to the switch *C*⁴, which in turn is operated to extend the connection to the operator's cord *O'*. The calling substation is thereupon provided with talking current over a circuit extending from ground *G*¹⁰ through one winding of the repeating coil 112, trunk 40 conductors 113 and 114, thence through the substation *A*³ and back over the other side of the line, over the trunk conductors 115 and 116 and through the relay 117 and a winding of the repeating coil 112 to the battery lead 120, thence through the battery *B*² to ground. The relay 117, upon energizing, 45 completes a holding circuit for the switches *C*³ and *C*⁴, which circuit extends from ground *G*¹¹ through the front contact of the armature 121, relay 122 (which corresponds in function to the relay 81 in Fig. 1), contact 222, windings of the switch *C*⁴ and the contact 123 and windings of the switch *C*³ in multiple therewith to the battery lead 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

tion with the cord *O'* a circuit is closed extending from ground *G*¹² at the cord through the relay 124, thence through the contacts 125 and 126 and through the windings of the meter magnet 56 and the cut-off relay 54 in multiple to the battery lead 120. The cut-off relay is energized by this current and operates to disconnect the line relay from the line, while the meter magnet 56 does not receive sufficient current in series with the relay 124 to be operatively energized. The relay 124 in the cord, upon energizing, completes the circuit of the lamp 127, which circuit extends from ground *G*¹³ through the back contact of the armature 128 and the front contact of the armature 129 and the lamp 127 to the battery lead. The operator, upon noting the signal displayed by the lamp 127, inquires of the calling subscriber the number of the line desired and then inserts the plug *P'* (Fig. 4) into a multiple jack *J*³ of the desired line. Upon the insertion of the plug *P'* into the jack *J*³ a circuit is closed from grounds *G*¹³ and *G*¹⁴ in the cord through the relays 130 and 131 in multiple, thence through the third conductors of the plug *P'* and the jack *J*³ and through the cut-off relay 132 and the meter magnet 133 of the called line in multiple to the battery lead 120. The relays 130, 131 and 132 are all operated over this circuit, the meter magnet 133, however, not receiving sufficient current to be operatively energized. The relay 130 in the cord, upon energizing, opens the circuit of the lamp 127, while the relay 131, upon energizing, closes the contact 133^a in the talking circuit and also closes a circuit extending from ground *G*¹⁴ through the contact 135, contact 136 and the relay 137 to battery. The relay 137, upon energizing, closes a circuit extending from ground *G*¹⁴ through the contacts 135 and 138 and the meter magnet 139 to the battery lead 120. A second circuit is closed extending from ground *G*¹⁴ through the contacts 135 and 140, lamp 141 and the relay 142 to the battery lead 120. The lamp 141 is lighted and the relay 142 energized over this latter circuit. The relay 142, upon energizing, forms a locking circuit for itself through the contact 143, independent of the contacts of the relay 137, and breaks the circuit of the relay 137 at the contact 136. The relay 137, which is slightly slow acting, deenergizes shortly and breaks the circuit of the meter magnet 139. It will thus be seen that as a result of the energization of the relay 131 upon the insertion of the plug *P* into the jack *J*², the calling supervisory lamp 141 is lighted and a single impulse is transmitted through the meter magnet 139 to register the call on the totalizing meter 58. Since the relay 142, upon energizing, becomes locked up through its own contact, no more impulses can be transmitted through 130

the meter magnet 139 until the plug has been withdrawn from the jack.

The called subscriber is signaled through the medium of the ringing key 144 in the same manner as described in connection with Fig. 1. Upon the response of the called subscriber the called substation is provided with talking current from the battery B² through the two windings of the repeating coil 112 and the answering supervisory relay 145 in the usual manner. The relay 145, upon energizing, closes a shunt around the lamp 141 through the relay 146, said shunt extending from ground G¹⁴ through the contacts 135 and 147 and the relay 146 to the relay 142. The relay 146 receives enough current in this circuit to be operatively energized and shunts enough current away from the lamp 141 to cause it to be extinguished to signify to the operator that the called subscriber has answered. The relay 146, upon energizing, closes an energizing circuit through the relay 148 by way of the contacts 135, 149 and 150. The relay 148, upon energizing, closes a circuit through the relay 152 by way of the contacts 135 and 153. The relay 152, upon energizing, closes a locking circuit for itself at the contact 154 and breaks the circuit of the relay 148, which, being slow acting, after a short interval, deenergizes. In its energized position the relay 148 closes a circuit extending from ground G¹⁵ through the battery B³, relay 156, contact 157, thence back through the contacts 125 and 126 of the switches C⁶ and C³, and through the meter magnet 56 and the cut-off relay 54 to the battery lead 120, thence through the battery B² to ground. It will be seen that in this circuit the batteries B³ and B² are connected in series, whereby the current in the meter magnet 56 is increased sufficiently to cause said magnet to operate the meter. At the cord O' the energization of the relay 156 serves to close the circuit of the meter magnet 158, whereby the effective call meter is operated once. Since the energization of the relay 148 is only momentary, the relay 156 is energized only for an instant and the current in the subscriber's meter magnet 56 is increased only momentarily. The meter magnet 56, however, does not restore to normal position upon the return of its energizing current to its original strength, however, as said magnet is preferably arranged so that, although it cannot be operated by its original current, it may be maintained in its operated position by said current. Since the relay 152 in the cord, upon being once energized, becomes locked through its own contact, the relay 148 cannot cause more than a single impulse to be transmitted through the meter magnets 56 and 158 for each call.

65 Upon the completion of the conversation

the operator is given the usual disconnect signals upon the hanging up of the receivers at the calling and called substations. The hanging up of the receivers permits the relays 145 and 117 to deenergize. The relay 145, upon deenergizing, removes the shunt from around the lamp 141 and allows it to become lighted again. The relay 117, upon deenergizing, closes the circuit of the lamp 127 by way of the back contacts of the armature 121 and the front contact of the armature of the relay 124. Upon the removal of the plug from the jack by the operator all the relays in the cord circuit which were locked up as a result of the insertion of the plug in the jack, or upon the response of the called subscriber, become deenergized, and the relay 130, upon deenergizing, destroys the holding circuit of the switches C³ and C⁶, allowing them to be restored to normal position, whereupon the relay 124 in the holding circuit becomes deenergized and extinguishes the lamp 127.

While I have illustrated my invention in connection with a semi-automatic telephone system of a particular type, and in which certain types of automatic switches are employed, it is, of course, to be understood that my invention is not limited to use in connection with such systems, but that it is capable of use in connection with many other semi-automatic systems in which various types of automatic switches are employed.

What I claim as my invention is:—

1. In a telephone system, a calling and a called subscriber's line, a manual operator's cord circuit for establishing connection with the called line, primary and secondary trunk-selecting switches for establishing connection from a calling line to said cord circuit, said secondary switches operating in response to the operation of said primary switches, a meter on said calling line, and means for automatically operating said meter upon the response of the called subscriber.

2. In a telephone system, a plurality of subscribers' lines, a plurality of operators' cord circuits for connecting with a called subscriber's line, a trunk-selecting switch on each of said subscribers' lines, a master switch for controlling a group of said trunk switches for preselecting an idle cord, a meter for registering the calls, and means for automatically operating said meter upon the response of the called subscriber.

3. In a telephone system, a plurality of subscribers' lines, a plurality of operators' cord circuits for connecting with a called subscriber's line, a primary trunking switch on each subscriber's line, a secondary trunking switch, a master switch for controlling a group of said primary trunking switches for automatically selecting a trunk extending to said secondary trunking switch, means

for then operating said second trunking switch for automatically selecting an idle cord, a meter for registering calls, and means for automatically operating said meter upon 5 the response of the called subscriber.

4. In a telephone system, a plurality of subscribers' lines, automatic means for establishing a talking circuit between two of said lines, a meter for registering the calls, 10 an operating magnet therefor, means for transmitting current of one strength through said magnet during the establishment of such connection, and means for transmitting a strengthened impulse through said magnet over a circuit exclusive of the talking 15 circuit to operate the same by the called subscriber.

5. In a telephone system, a plurality of subscribers' lines, automatic means for establishing a talking circuit between two of 20 said lines, a meter for registering the calls, an operating magnet therefor, means for transmitting current of one strength through said magnet during the establishment of such connection, and means for automatically 25 transmitting a strengthened impulse through said magnet over a circuit exclusive of the talking circuit to operate the same by the called subscriber.

30 6. In a telephone system, a calling and a called subscriber's line, means including automatic selecting switches and a manual operator's cord circuit for establishing a talking circuit between said lines, a meter for 35 registering calls, an operating magnet therefor, means for transmitting current of one strength through said magnet over a circuit independent of said talking circuit during the establishment of said connection between 40 said subscribers' lines, and means for transmitting a strengthened impulse through said magnet to operate the same by the called subscriber.

7. In a telephone system, a calling and a 45 called subscriber's line, a manual operator's cord circuit for connecting with the called line, a trunk-selecting switch on the calling line for selecting an idle operator's cord, a meter for registering calls, an operating 50 magnet therefor, means for transmitting current of one strength through said magnet during the establishment of said connection between said subscribers' lines, and means for transmitting a strengthened 55 impulse through said magnet to operate the same by the called subscriber.

8. In a telephone system, a calling and a called subscriber's line, a manual operator's cord circuit for establishing connection with 60 the called line, primary and secondary trunk-selecting switches for establishing connection from a calling line to said cord circuit, a meter on said calling line, an operating magnet therefor, means for transmitting current of one strength through 65

said magnet during the establishment of said connection between said subscribers' lines, and means for transmitting a strengthened impulse through said magnet to operate the same by the called subscriber. 70

9. In a telephone system, a plurality of subscribers' lines, a plurality of operators' cord circuits for connecting with a called subscriber's line, a trunk-selecting switch on each of said subscribers' lines, a master 75 switch for controlling a group of said trunk switches for preselecting an idle cord, a meter for registering the calls, an operating magnet therefor, means for transmitting current of one strength through said magnet during the establishment of said connection between said subscribers' lines, and means for transmitting a strengthened impulse through said magnet to operate the same by the called subscriber. 80

10. In a telephone system, a plurality of subscribers' lines, a plurality of operators' cord circuits for connecting with a called subscriber's line, a trunking switch on each subscriber's line, a master switch for controlling a group of said trunking switches for automatically selecting a trunk extending to a secondary trunking switch, means for then operating said second trunking switch for automatically selecting an idle 95 cord, a meter for registering calls, an operating magnet therefor, means for transmitting current of one strength through said magnet during the establishment of said connection between said subscribers' lines, 100 and means for transmitting a strengthened impulse through said magnet to operate the same by the called subscriber.

11. In a telephone system, a calling and a called subscriber's line, means including 105 automatic selecting switches and a manual operator's cord circuit for establishing a talking circuit between said lines, a meter for registering calls, a magnet for operating said meter each time the said magnet is 110 energized, means whereby the response of the called subscriber causes a momentary impulse of current to be transmitted through said meter over a circuit independent of said talking circuit to operate the same, and 115 means for rendering said impulse-transmitting device inoperative after one impulse is transmitted.

12. In a telephone system, a calling and a called subscriber's line, a manual operator's cord circuit for connecting with the called line, a trunk-selecting switch individual to the calling line for selecting an idle operator's cord, a meter for registering calls, a magnet for operating said meter each 120 time the said magnet is energized, means whereby the response of the called subscriber causes a momentary impulse of current to be transmitted through said meter to operate the same, and means for render- 125 130

ing said impulse-transmitting device inoperative after one impulse is transmitted.

13. In a telephone system, a calling and a called subscriber's line, a manual operator's cord circuit for establishing connection with the called line, primary and secondary trunk-selecting switches for establishing connection from a calling line of said cord circuit, a meter on said calling line, a magnet for operating said meter each time the said magnet is energized; means whereby the response of the called subscriber causes a momentary impulse of current to be transmitted through said meter to operate the same, and means for rendering said impulse-transmitting device inoperative after one impulse is transmitted. 80

14. In a telephone system, a plurality of subscribers' lines, a plurality of operators' cord circuits for connecting with a called subscriber's line, a trunk-selecting switch on each of said subscribers' lines, a master switch for controlling a group of said trunk switches for preselecting an idle cord, a meter for registering the calls, means whereby the response of the called subscriber causes a momentary impulse of current to be transmitted through said meter to operate the same, and means for rendering said impulse-transmitting device inoperative after one impulse is transmitted. 90

15. In a telephone system, a plurality of subscribers' lines, a plurality of operators' cord circuits for connecting with a called subscriber's line, a trunking switch on each subscriber's line, a master switch for controlling a group of said trunking switches for automatically selecting a trunk extending to a secondary trunking switch, means for then operating said second trunking switch for automatically selecting an idle cord, a meter for registering calls, means whereby the response of the called subscriber causes a momentary impulse of current to be transmitted through said meter to operate the same, and means for rendering said impulse-transmitting device inoperative after one impulse is transmitted. 100

16. In a telephone system, a plurality of subscribers' lines, automatic means for establishing a talking circuit between two of said lines, a meter for registering said connections, an operating magnet therefor, means for transmitting current of one strength through said magnet over a circuit independent of said talking circuit during the establishment of such connection, means for transmitting a momentary strengthened impulse of current through said magnet to operate the same upon the response of the called subscriber, and means for rendering said strengthened impulse-transmitting means inoperative after one impulse is transmitted. 115

17. In a telephone system, a plurality of

subscribers' lines, automatic means for establishing a talking circuit between two of said lines, a meter for registering said connections, an operating magnet therefor, means for transmitting current of one strength through said magnet during the establishment of such connection over a circuit independent of said talking circuit, means for automatically transmitting a momentary strengthened impulse of current through said magnet to operate the same upon the response of the called subscriber, and means for rendering said strengthened impulse-transmitting means inoperative after one impulse is transmitted. 80

18. In a telephone system, a calling and a called subscriber's line, a manual operator's cord circuit for connecting with the called line, primary and secondary trunk selecting switches controlled from the calling line for selecting an idle operator's cord, a release circuit for releasing said switch, a meter comprising a magnet for registering calls, means for automatically operating said meter upon the response of the called subscriber, and another magnet for closing the release circuit. 90

19. In a telephone system, calling and called subscribers' lines, a manual operator's cord circuit for establishing connection with the called line, primary and secondary trunk selecting switches controlled by the calling line for establishing connection to the cord circuit, a meter on said calling line and means for automatically operating said meter upon the response of the called subscriber. 100

20. In a telephone system, a plurality of subscribers' lines, means controlled over two sides of a calling line in series for establishing a talking circuit between two of said lines, a meter for registering said connection, an operating magnet therefor, means for transmitting current of one strength through said magnet during the establishment of such connection over a circuit independent of said talking circuit, and means controlled by the called subscriber for raising the voltage through said magnet to operate the same upon the response of the called subscriber. 110

21. In a telephone system, a plurality of subscribers' lines, means controlled over two sides of a calling line in series for establishing a talking circuit between two of said lines, a meter for registering said connection, an operating magnet therefor, means for transmitting current of one strength through said magnet during the establishment of such connection over a circuit independent of said talking circuit, and means for raising the voltage momentarily through said magnet to operate the same by the called subscriber. 125

22. In an automatic telephone system, a 130

- plurality of subscribers' lines, means controlled over two sides of a calling line in series for establishing a talking circuit between two of said lines, a meter for registering said connection, an operating magnet therefor, means for transmitting current of one strength through said magnet during the establishment of such connection over a circuit independently of said talking circuit, and means for automatically raising the voltage through said magnet to operate the same upon the response of the called subscriber.
23. In an automatic telephone system, a plurality of subscribers' lines, means controlled over two sides of a calling line in series for establishing a talking circuit between two of said lines, a meter for registering said connection, an operating magnet therefor, means for transmitting current of one strength through said magnet during the establishment of such connection over a circuit independent of said talking circuit, and means for automatically raising the voltage momentarily through said magnet to operate the same upon the response of the called subscriber.
24. In a telephone system, a calling and a called subscriber's line, means including automatic selecting switches and a manual operator's cord circuit for establishing a talking circuit between said lines, a meter for registering calls, an operating magnet therefor, means for transmitting current of one strength through said magnet over a circuit independent of said talking circuit during the establishment of said connection between said subscribers' lines, and means for transmitting an impulse of strengthened voltage through said magnet to operate the same by the called subscriber.
25. In a telephone system, a calling and a called subscriber's line, a manual operator's cord circuit for connecting with the called line, a trunk-selecting switch on the calling line for selecting an idle operator's cord, a meter for registering calls, an operating magnet therefor, means for transmitting current of one strength through said magnet during the establishment of said connection between said subscribers' lines, and means for transmitting an impulse of strengthened voltage through said magnet to operate the same by the called subscriber.
26. In a telephone system, a calling and a called subscriber's line, a manual operator's cord circuit for establishing connection with the called line, primary and secondary trunk-selecting switches for establishing connection from a calling line to said cord circuit, a meter on said calling line, an operating magnet therefor, means for transmitting current of one strength through said magnet during the establishment of said connection between said subscribers' lines, and means for transmitting an impulse of strengthened voltage through said magnet to operate the same by the called subscriber.
27. In a telephone system, a plurality of subscribers' lines, a plurality of operators' cord circuits for connecting with a called subscriber's line, a trunk-selecting switch on each of said subscribers' lines, a master switch for controlling a group of said trunk switches for preselecting an idle cord, a meter for registering the calls, an operating magnet therefor, means for transmitting current of one strength through said magnet during the establishment of said connection between said subscribers' lines, and means for transmitting an impulse of strengthened voltage through said magnet to operate the same by the called subscriber.
28. In a telephone system, a plurality of subscribers' lines, a plurality of operators' cord circuits for connecting with a called subscriber's line, a trunking switch on each subscriber's line, a master switch for controlling a group of said trunking switches for automatically selecting a trunk extending to a secondary trunking switch, means for then operating said second trunking switch for automatically selecting an idle cord, a meter for registering calls, an operating magnet therefor, means for transmitting current of one strength through said magnet during the establishment of said connection between said subscribers' lines, and means for transmitting an impulse of strengthened voltage through said magnet to operate the same by the called subscriber.
29. In a telephone system, a plurality of subscribers' lines, automatic means for establishing a talking circuit between two of said lines, a meter for registering said connections, an operating magnet therefor, means for transmitting current of one strength through said magnet over a circuit independent of the talking circuit during the establishment of such connection, means for transmitting a strengthened impulse of current through said magnet to operate the same upon the response of the called subscriber, and means for rendering said strengthened impulse-transmitting means inoperative after one impulse is transmitted.
30. In a telephone system, a plurality of subscribers' lines, automatic means for establishing a talking circuit between two of said lines, a meter for registering said connections, an operating magnet therefor, means for transmitting current of one strength through said magnet over a circuit independent of the talking circuit during the establishment of such connection, means for automatically transmitting a strengthened impulse of current through said magnet to operate the same upon the response of the called subscriber, and means for rendering

said strengthened impulse-transmitting means inoperative after one impulse is transmitted.

31. In a telephone system, a calling and a called subscriber's line, means including primary and secondary trunk selecting switches and a manual operator's cord circuit for establishing a connection between said lines, said secondary switches operating in response to the operation of said primary switches, a meter for registering calls, means whereby the response of a called subscriber causes a momentary impulse of current to be transmitted through said meter to operate the same, and means for rendering said impulse transmitting device inoperative after one impulse is transmitted.

32. In a telephone system, a calling and a called subscriber's line, a manual operator's cord circuit for connecting with the called line, primary and secondary trunk selecting switches for selecting an idle operator's cord circuit, said secondary switches operating in response to the operation of said primary switches, a meter for registering calls, means whereby the response of the called subscriber causes a momentary impulse of current to be transmitted through said meter to operate the same, and means for rendering said impulse transmitting device inoperative after one impulse is transmitted.

33. In a telephone system, a calling and a called subscriber's line, means including automatic selecting switches and a manual operator's cord circuit for establishing a talking circuit between said lines, a meter for registering calls, means including a relay whereby the response of the called subscriber causes a momentary impulse of current to be transmitted through said meter over a circuit independent of said talking circuit to operate the same, and means for rendering the said relay inoperative after one impulse is transmitted.

34. In a telephone system, a calling and a called subscriber's line, a manual operator's cord circuit for connecting with the called line, a trunk selecting switch on the calling line for selecting an idle operator's cord circuit, a meter for registering calls, means including a relay whereby the response of the called subscriber causes a momentary impulse of current to be transmitted through said meter to operate the same and means for rendering said relay inoperative after one impulse is transmitted.

35. In a telephone system, a temporarily established connection between a calling and called line including a plurality of automatic trunking switches, a circuit independent of the talking conductors and extending through a plurality of said switches, a call register individual to the calling line included in said circuit, and mechanism controlled by the called subscriber for trans-

mitting a momentary current impulse over said circuit to operate said register.

36. In a telephone system, a temporarily established connection between a calling and called line, including a plurality of automatic trunking switches, a circuit independent of the talking conductors and extending through a plurality of said switches, a call register individual to the calling line included in said circuit, and automatic means actuated upon the response of the called subscriber for transmitting a momentary current impulse over said circuit to operate said register.

37. In a telephone system, a temporarily established connection between a calling and called line including a plurality of automatic trunking switches, a circuit independent of the talking conductors and extending through a plurality of said switches, a call register individual to the calling line included in said circuit, and automatic electromagnetic means actuated upon the response of the called subscriber for transmitting a momentary current impulse over said circuit to operate said register.

38. In a telephone system, a temporarily established connection between a calling and called line including an automatic trunking switch individual to the calling line, a circuit independent of the talking conductors including a movable contact in said switch, a call register individual to the calling line included in said circuit, and mechanism controlled by the called subscriber for transmitting a momentary current impulse over said circuit to operate said register.

39. In a telephone system, a temporarily established connection between a calling and called line including an automatic trunking switch individual to the calling line, a circuit independent of the talking conductors including a movable contact in said switch, a call register individual to the calling line included in said circuit, and automatic means actuated upon the response of the called subscriber for transmitting a momentary current impulse over said circuit to operate said register.

40. In a telephone system, a temporarily established connection between a calling and called line including an automatic trunking switch individual to the calling line, a circuit independent of the talking conductors including a movable contact in said switch, a call register individual to the calling line included in said circuit, and electromagnetic automatic means actuated upon the response of the called subscriber for transmitting a momentary current impulse over said circuit to operate said register.

41. In a telephone system, a temporarily established connection between a calling and a called line including an automatic trunking switch and an operator's cord circuit,

a circuit independent of the talking conductors and including a movable contact of said switch, a call register individual to the calling line included in said circuit, and 5 mechanism controlled by the called subscriber for transmitting a momentary current impulse over said circuit to operate said register.

42. In a telephone system, a temporarily 10 established connection between a calling and a called line including an automatic trunking switch and an operator's cord circuit, a circuit independent of the talking conductors and including a movable contact of said 15 switch, a call register individual to the calling line included in said circuit, and automatic means actuated upon in response of the called subscriber for transmitting a momentary current impulse over said circuit 20 to operate said register.

43. In a telephone system, a temporarily established connection between a calling and a called line including an automatic trunking switch and an operator's cord circuit, a 25 circuit independent of the talking conductors and including a movable contact of said switch, a call register individual to the calling line included in said circuit, and electromagnetic automatic means actuated upon the 30 response of the called subscriber for transmitting a momentary current impulse over said circuit to operate said register.

44. In a telephone system, a temporarily 35 established connection between a calling and called line including a non-numerical automatic trunking switch individual to the calling line, a circuit independent of the talking conductors including a movable contact in said switch, a call register individual to 40 the calling line included in said circuit, and mechanism controlled by the called subscriber for transmitting a momentary current impulse over said circuit to operate said register.

45. In a telephone system, a temporarily 45 established connection between a calling and called line including a non-numerical automatic trunking switch individual to the calling line, a circuit independent of the talking 50 conductors including a movable contact in said switch, a call register individual to the calling line included in said circuit, and automatic means actuated upon the response 55 of the called subscriber for transmitting a momentary current impulse over said circuit to operate said register.

46. In a telephone system, a temporarily 60 established connection between a calling and called line including a non-numerical automatic trunking switch individual to the calling line, a circuit independent of the talking 65 conductors including a movable contact in said switch, a call register individual to the calling line included in said circuit, and electromagnetic automatic means actuated

upon the response of the called subscriber for transmitting a momentary current impulse over said circuit to operate said register.

47. In a telephone system, a temporarily 70 established connection between a calling and a called line including an automatic trunking switch individual to the calling line, a cut-off relay and a call register for the calling line, a common circuit for said relay and 75 register including a battery, said register being irresponsible to normal current flow in said circuit, and mechanism controlled by the response of the called subscriber for increasing the current flow in said circuit to 80 operate said register.

48. In a telephone system, a temporarily 85 established connection between a calling and a called line including an automatic trunking switch individual to the calling line, a cut-off relay and a call register for the calling line, a common circuit for said relay and 90 register including a battery, said register being irresponsible to normal current flow in said circuit, and automatic devices for increasing the current flow in said circuit to operate said register prior to conversation over said connection.

49. In a telephone system, a temporarily 95 established connection between a calling and a called line including an automatic trunking switch individual to the calling line, a cut-off relay and a call register for the calling line, a common circuit for said relay and 100 register including a battery, said register being irresponsible to normal current flow in said circuit, a second battery, and automatic means for connecting said second battery in series with said first battery in said circuit to increase the current flow therein 105 to operate said register.

50. In a telephone system, a temporarily 110 established connection between a calling and a called line including an automatic trunking switch individual to the calling line, a cut-off relay and a call register for the calling line, a common circuit for said relay and 115 register including a battery, said register being irresponsible to normal current flow in said circuit, a second battery, and automatic means controlled by the response of the called subscriber for including said second battery in said circuit to increase the current flow therein to operate said register.

51. In a telephone system, a temporarily 120 established connection between a calling and a called line including an automatic trunking switch individual to the calling line, a cut-off relay and a call register for the calling line, a common circuit for said relay and 125 register including a battery, said register being irresponsible to normal current flow in said circuit, and automatic devices for momentarily increasing the current flow in said circuit to operate said register. 130

52. In a telephone system, a temporarily established connection between a calling and a called line including an automatic trunking switch individual to the calling line, a cut-off relay and a call register for the calling line, a common circuit for said relay and register including a battery, said register being irresponsible to normal current flow in said circuit, and mechanism controlled by the called subscriber for momentarily increasing the current flow in said circuit to operate said register. 70
53. In a telephone system, a temporarily established connection between a calling and a called line including an automatic trunking switch individual to the calling line, a cut-off relay and a call register for the calling line, a common circuit for said relay and register including a battery, said register being irresponsible to normal current flow in said circuit, and electromagnetic mechanism controlled by the response of the called subscriber for increasing the current flow in said circuit to operate said register. 80
54. In a telephone system, a temporarily established connection between a calling and a called line including an automatic trunking switch individual to the calling line, a cut-off relay and a call register for the calling line, a common circuit for said relay and register including a battery, said register being irresponsible to normal current flow in said circuit, a second battery, and automatic electromagnetic means for connecting said second battery in series with said first battery in said circuit to increase the current flow therein to operate said register. 90
55. In a telephone system, a temporarily established connection between a calling and a called line including an automatic trunking switch individual to the calling line, a cut-off relay and a call register for the calling line, a common circuit for said relay and register including a battery, said register being irresponsible to normal current flow in said circuit, a second battery, and electromagnetic automatic means controlled by the response of the called subscriber for including said second battery in said circuit to increase the current flow therein to operate said register. 105
56. In a telephone system, a temporarily established connection between a calling and a called line including an automatic trunking switch individual to the calling line, a cut-off relay and a call register for the calling line, a common circuit for said relay and register including a battery, said register being irresponsible to normal current flow in said circuit, and electromagnetic mechanism controlled by the called subscriber for momentarily increasing the current flow in said circuit to operate said register. 120
57. In a telephone system, a temporarily established connection between a calling and a called line including a plurality of automatic trunking switches, a cut-off relay and a call register for the calling line, a common circuit for said relay and register including a battery and movable contacts in said switches, said register being irresponsible to normal current flow in said circuit, and mechanism controlled by the response of the called subscriber for increasing the current flow in said circuit to operate said register. 125
58. In a telephone system, a temporarily established connection between a calling and a called line including a plurality of automatic trunking switches, a cut-off relay and a call register for the calling line, a common circuit for said relay and register including a battery and movable contacts in said switches, said register being irresponsible to normal current flow in said circuit, and automatic devices for increasing the current flow in said circuit to operate said register prior to conversation over said connection. 130
59. In a telephone system, a temporarily established connection between a calling and a called line including a plurality of automatic trunking switches, a cut-off relay and a call register for the calling line, a common circuit for said relay and register including a battery and movable contacts in said switches, said register being irresponsible to normal current flow in said circuit, a second battery and automatic means for connecting said second battery in series with said first battery in said circuit to increase the current flow therein to operate said register. 100
60. In a telephone system, a temporarily established connection between a calling and a called line including a plurality of automatic trunking switches, a cut-off relay and a call register for the calling line, a common circuit for said relay and register including a battery and movable contacts in said switches, said register being irresponsible to normal current flow in said circuit, a second battery and automatic means controlled by the response of the called subscriber for including said second battery in said circuit to increase the current flow therein to operate said register. 110
61. In a telephone system, a temporarily established connection between a calling and a called line including a plurality of automatic trunking switches, a cut-off relay and a call register for the calling line, a common circuit for said relay and register including a battery and movable contacts in said switches, said register being irresponsible to normal current flow in said circuit, and automatic devices for momentarily increasing the current flow in said circuit to operate said register. 120
62. In a telephone system, a temporarily

established connection between a calling and a called line including a plurality of automatic trunking switches, a cut-off relay and a call register for the calling line, a common circuit for said relay and register including a battery and movable contacts in said switches, said register being irresponsive to normal current flow in said circuit, and mechanism controlled by the called subscriber for momentarily increasing the current flow in said circuit to operate said register.

63. In a telephone system, a temporarily established connection between a calling and a called line including a plurality of automatic trunking switches, a cut-off relay and a call register for the calling line, a common circuit for said relay and register including a battery and movable contacts in said switches, said register being irresponsive to normal current flow in said circuit, and electromagnetic mechanism controlled by the response of the called subscriber for increasing the current flow in said circuit to operate said register.

64. In a telephone system, a temporarily established connection between a calling and a called line including a plurality of automatic trunking switches, a cut-off relay and a call register for the calling line, a common circuit for said relay and register including a battery and movable contacts in said switches, said register being irresponsive to normal current flow in said circuit, a second battery and electromagnetic automatic means for connecting said second battery in series with said first battery in said circuit to increase the current flow therein to operate said register.

65. In a telephone system, a temporarily established connection between a calling and a called line including a plurality of automatic trunking switches, a cut-off relay and a call register for the calling line, a common circuit for said relay and register including a battery and movable contacts in said switches, said register being irresponsive to normal current flow in said circuit, a second battery, and electromagnetic automatic means controlled by the response of the called subscriber for including said second battery in said circuit to increase the current flow therein to operate said register.

66. In a telephone system, a temporarily established connection between a calling and a called line including a plurality of automatic trunking switches, a cut-off relay and a call register for the calling line, a common circuit for said relay and register including a battery and movable contacts in said switches, said register being irresponsive to normal current flow in said circuit, and electromagnetic mechanism controlled by the called subscriber for momen-

tarily increasing the current flow in said circuit to operate said register.

67. In a telephone system, a temporarily established connection between a calling and called line including an automatic 70 trunking switch, a circuit for making the calling line busy including a movable contact of said switch and a battery, a call register in a branch of said circuit and irresponsive to normal current flow therein, 75 and mechanism controlled by the response of the called subscriber for increasing the current flow in said circuit to operate said register.

68. In a telephone system, a temporarily 80 established connection between a calling and called line including an automatic trunking switch, a circuit for making the calling line busy including a movable contact of said switch and a battery, a call 85 register in a branch of said circuit and irresponsive to normal current flow therein, and automatic devices for increasing the current flow in said circuit to operate said register prior to conversation over said connection.

69. In a telephone system, a temporarily established connection between a calling and called line including an automatic 95 trunking switch, a circuit for making the calling line busy including a movable contact of said switch and a battery, a call register in a branch of said circuit and irresponsive to normal current flow therein, a second battery, and automatic means for 100 connecting said second battery in series with said first battery in said circuit to increase the current flow therein to operate said register.

70. In a telephone system, a temporarily 105 established connection between a calling and called line including an automatic trunking switch, a circuit for making the calling line busy including a movable contact of said switch and a battery, a call 110 register in a branch of said circuit and irresponsive to normal current flow therein, a second battery, and automatic means controlled by the response of the called subscriber for including said second battery 115 in said circuit to increase the current flow therein to operate said register.

71. In a telephone system, a temporarily established connection between a calling and called line including an automatic 120 trunking switch, a circuit for making the calling line busy including a movable contact of said switch and a battery, a call register in a branch of said circuit and irresponsive to normal current flow therein, 125 and automatic devices for momentarily increasing the current flow in said circuit to operate said register.

72. In a telephone system, a temporarily established connection between a calling 130

and called line including an automatic trunking switch, a circuit for making the calling line busy including a movable contact of said switch and a battery, a call 5 register in a branch of said circuit and responsive to normal current flow therein, and mechanism controlled by the called subscriber for momentarily increasing the current flow in said circuit to operate said 10 register.

73. In a telephone system, a temporarily established connection between a calling and called line including an automatic trunking switch, a circuit for making the calling 15 line busy including a movable contact of said switch and a battery, a call register in a branch of said circuit and responsive to normal current flow therein, and electromagnetic mechanism controlled by the response of the called subscriber for increasing the current flow in said circuit to operate said 20 register.

74. In a telephone system, a temporarily established connection between a calling and called line including an automatic trunking switch, a circuit for making the calling 25 line busy including a movable contact of said switch and a battery, a call register in a branch of said circuit and responsive to normal current flow therein, a second battery, and electromagnetic automatic means 30 for connecting said second battery in series with said first battery in said circuit to increase the current flow therein to operate 35 said register.

75. In a telephone system, a temporarily established connection between a calling and called line including an automatic trunking switch, a circuit for making the calling 40 line busy including a movable contact of said switch and a battery, a call register in a branch of said circuit and responsive to normal current flow therein, a second battery, and electromagnetic automatic means 45 controlled by the response of the called subscriber for including said second battery in said circuit to increase the current flow therein to operate said register.

76. In a telephone system, a temporarily established connection between a calling and called line including an automatic trunking switch, a circuit for making the calling 50 line busy including a movable contact of said switch and a battery, a call register in a branch of said circuit and responsive to normal current flow therein, and electromagnetic mechanism controlled by the called subscriber for momentarily increasing the current flow in said circuit to operate said 55 register.

77. In a telephone system, a temporarily established connection between a calling and a called line including a non-numerical automatic trunking switch individual to the 60 calling line, a cut-off relay and a call register being irresponsive to normal current flow in said circuit, and mechanism controlled by the response of the called subscriber for increasing the current flow in said circuit to operate said register.

ter for the calling line, a common circuit for said relay and register including a battery, said register being irresponsive to normal current flow in said circuit, and mechanism controlled by the response of the called 70 subscriber for increasing the current flow in said circuit to operate said register.

78. In a telephone system, a temporarily established connection between a calling and a called line including a non-numerical automatic trunking switch individual to the calling line, a cut-off relay and a call register for the calling line, a common circuit for said relay and register including a battery, 75 said register being irresponsive to normal current flow in said circuit, and automatic devices for increasing the current flow in said circuit to operate said register prior to conversation over said connection.

79. In a telephone system, a temporarily established connection between a calling and a called line including a non-numerical automatic trunking switch individual to the calling line, a cut-off relay and a call register for the calling line, a common circuit 80 for said relay and register including a battery, said register being irresponsive to normal current flow in said circuit, a second battery, and automatic means for connecting said second battery in series with said 85 first battery in said circuit to increase the current flow therein to operate said register.

80. In a telephone system, a temporarily established connection between a calling and a called line including a non-numerical automatic trunking switch individual to the calling line, a cut-off relay and a call register for the calling line, a common circuit for said relay and register including a battery, 90 said register being irresponsive to normal current flow in said circuit, a second battery, and automatic means controlled by the response of the called subscriber for including said second battery in said circuit to increase the current flow therein to operate 95 said register.

81. In a telephone system, a temporarily established connection between a calling and a called line including a non-numerical automatic trunking switch individual to the calling line, a cut-off relay and a call register for the calling line, a common circuit for said 100 relay and register including a battery, said register being irresponsive to normal current flow in said circuit, and automatic devices 105 for momentarily increasing the current flow in said circuit to operate said register.

82. In a telephone system, a temporarily established connection between a calling and a called line including a non-numerical automatic trunking switch individual to the calling line, a cut-off relay and a call register for the calling line, a common circuit for said relay and register including a battery, 110 said register being irresponsive to normal current flow in said circuit, and mechanism controlled by the response of the called subscriber for increasing the current flow in said circuit to operate said register.

current flow in said circuit, and mechanism controlled by the called subscriber for momentarily increasing the current flow in said circuit to operate said register.

- 5 83. In a telephone system, a temporarily established connection between a calling and a called line including a non-numerical automatic trunking switch individual to the calling line, a cut-off relay and a call register 50 for the calling line, a common circuit for said relay and register including a battery, said register being irresponsible to normal current flow in said circuit, and electromagnetic mechanism controlled by the response of 55 the called subscriber for increasing the current flow in said circuit to operate said register.
84. In a telephone system, a temporarily established connection between a calling and 20 a called line including a non-numerical automatic trunking switch individual to the calling line, a cut-off relay and a call register for the calling line, a common circuit for said relay and register including a battery, 25 said register being irresponsible to normal current flow in said circuit, a second battery and electromagnetic automatic means for connecting said second battery in series with said first battery in said circuit to 30 increase the current flow therein to operate said register.

85. In a telephone system, a temporarily established connection between a calling and a called line including a non-numerical automatic trunking switch individual to the calling line, a cut-off relay and a call register for the calling line, a common circuit for said relay and register including a battery, said register being irresponsible to 35 normal current flow in said circuit, a second battery, and electromagnetic automatic means controlled by the response of the called subscriber for including said second battery in said circuit to increase the current 40 flow therein to operate said register.

86. In a telephone system, a temporarily established connection between a calling and

a called line including a non-numerical automatic trunking switch individual to the calling line, a cut-off relay and a call register for the calling line, a common circuit for said relay and register including a battery, 50 said register being irresponsible to normal current flow in said circuit, and electromagnetic mechanism controlled by the called 55 subscriber for momentarily increasing the current flow in said circuit to operate said register.

87. In a telephone system, a calling and a called subscriber's line, means including automatic selecting switches and a manual operator's cord circuit for establishing a talking circuit between said lines, a meter for registering calls, an operating magnet therefor, means for transmitting current of one 60 strength through said magnet over a circuit independent of said talking circuit during the establishment of said connection between said lines, and means controlled by the removal of the receiver at the called station for 65 transmitting a strengthened impulse through said magnet to operate the same upon the response of the called subscriber.

88. In a telephone system a plurality of subscribers' lines, means controlled over the 70 two sides of a calling line in series for establishing a talking circuit between two of said lines, a meter for registering said connection, an operating magnet therefor, means for transmitting current of one strength 75 through said magnet during the establishment of such connection over a circuit independent of said talking circuit, and means controlled by the removal of the receiver at the called station for raising the voltage 80 through said magnet to operate the same upon the response of the called subscriber.

Signed by me at Chicago, Cook county, Illinois, this 3rd day of August, 1912.

TALBOT G. MARTIN.

Witnesses:

ARTHUR J. RAY,
ALEX. E. WALKER.
